AIR DISTRIBUTOR

Paul D. Harrigan, Milford, Conn., assignor to Air Devices Incorporated, New York, N. Y., a corporation of New York

Application February 8, 1939, Serial No. 255,187

10 Claims. (Cl. 98—40)

This invention relates to air distributors, and more particularly to devices through which air may be introduced into a room or chamber for heating, ventilating, conditioning, or other purposes. Wherever air is introduced into a room, it is desirable that the air be diffused as much as possible in order that it does not take the form of a draft and blow directly, or even indirectly, upon the occupants of the room, whether the air be for the purpose of ventilation, for heating, or for a combination of the two, such as is present in the usual air-conditioning systems. Such drafts are not only disagreeable and result in discomfort, but are also unhealthful.

When air is discharged into a room, it is usually discharged through an air distributor such as a register or grill secured to a side wall of the room, or upon the ceiling thereof. It will be apparent that if the air is allowed to pass outwardly from the distributor, or in a direction away from the surface to which the distributor is secured, it will take the form of a more or less harmful draft, and that the ideal condition in introducing such air is to so arrange the distributor that the flow therefrom will be in a direction substantially parallel to the surface to which the distributor is attached, instead of outwardly from that surface. That is to say, if the distributor is a ceiling installation, the flow of air entering therethrough should be discharged therefrom in a horizontal plane substantially parallel to the ceiling so as not to blow downwardly, but to gradually diffuse downwardly, which diffusion will not be harmful or disagreeable to the occupants of the room.

Prior attempts have been made to realize the ideal condition in air distribution, and these devices have sometimes taken the form of a plurality of spaced and nested pyramidal or conical elements. Such elements are placed one below the other, and in the case of a ceiling installation, for example, they protrude to a considerable extent below the ceiling line so as to be objectionable to architects and interior designers from the standpoint of appearance. Moreover, such devices, while achieving to some extent the desired result, do not effect a truly horizontal distribution or flow of the air from the distributor.

One object of the present invention is to provide an air distributor or outlet member which will be substantially flush with the surface to which it is secured, and which will effect a discharge of air in a plane substantially parallel with said surface.

A still further object of the invention is the

provision of an air distributor in the form of a grill or the like, which will be of very limited depth so that it may readily be installed in a wall substantially flush with the surface thereof, and which distributor will be provided with means for effecting a discharge of the air passing therethrough in a plane substantially parallel with the surface of such wall.

A still further object of the invention is the provision of an air distributor of the type described, which will be of relatively simple construction and which may be economically manufactured, and at the same time be of pleasing appearance.

15 Still another object of the invention is the provision of an air distributor to be installed in a wall of a room or chamber to be supplied with air such that the distributor may receive air from an air duct substantially perpendicular to the wall, and change the direction of flow of such air so that it will be discharged in a plane substantially parallel to the wall.

To these and other ends the invention consists in the novel features and combinations of parts 20 to be hereinafter described and claimed.

In the drawings:

Fig. 1 is a face elevational view of an air distributor embodying my invention;

Fig. 2 is a rear view of the same;

30 Fig. 3 is a sectional view on line 3—3 of Fig. 1; Fig. 4 is a sectional view on line 4—4 of Fig. 2; and

35 Fig. 5 is a perspective view of the front or face of the distributor looking in the direction of the arrow 5 on Fig. 3.

It may be stated that when in the description reference is made to the partitions or wall of a room, it will be understood that this term may refer to the side wall or to the ceiling, as the device illustrated is adapted to be employed in either a ceiling or a side wall installation.

To illustrate a preferred embodiment of my invention, I have shown an air distributor comprising an outer frame member 10 which, as will be obvious from reference to the sectional views shown in Fig. 4, may be conveniently made V-shaped in cross-section, although it is to be understood that it is not limited to this particular shape. As shown, the outer edge or frame 10 is substantially square. Such shape, however, is merely for the purpose of illustration, and this frame which gives shape to the device may be rectangular, circular, oblong, or of any desired configuration.

Within this frame are provided a plurality of

elongated flat members 11 which may be termed plates. In the form of the device illustrated, these plates are arranged in hollow squares, one within the other, the sides thereof being substantially parallel to the sides of the frame. Such an arrangement provides, of course, for equal distribution of the air from the device in all directions. It will be understood, however, that the plates may merely be arranged in parallelism, if desired, without departing from the spirit of the invention. It may also be noted that in each quarter of the device comprised within the triangular portion between one of the edges and two diagonals meeting at the center, the plates 11 are arranged in parallel spaced relation, and this arrangement may be followed throughout the entire area of the distributor.

Referring particularly to Figs. 3, 4 and 5, it will be noted that, while one of the plates 11 is substantially parallel with the next adjacent plate, these plates do not lie in the same plane, but are tipped or inclined relatively to the general plane of the grid as a whole, which will, of course, be parallel to the plane of the wall surface to which the grid is attached. Tipping or inclining the plates 11 in this manner, in addition to the spacing thereof, provides for elongated openings therebetween, and from reference to Fig. 1, it will be noted that the forward edge of one plate may be spaced slightly within the rear edge of the next adjacent plate, so as to leave a narrow slot therebetween when looking directly toward the grill, as illustrated in Fig. 1. It may also be noted that the inner part 35 of the V-shaped border portion or frame 10 is parallel to the adjacent plate 11, and in reality serves as the end plate of the series.

As shown in Figs. 2 to 5, vanes 12 and 13 are provided on the rear faces of the plates 11. 40 Each of these vanes, as shown particularly in Figs. 4 and 5, is substantially triangular in shape, tapering substantially to a point at the rear edge of the plate, and being of sufficient width at the front edge to span the space between the adjacent plates. These vanes by reason of the fact that each is secured to two adjacent plates, serve to connect the plates together into a rigid frame. The lower edge 14 of such vanes, as shown in Fig. 4, will be secured directly to the plate upon which the vane is disposed.

With reference to Fig. 2, it will be noted that the plane of each of the vanes 12 is not perpendicular to the longitudinal dimension of the corresponding plate 11, but is inclined thereto, and while variation may be made in this respect, as illustrated, the vanes 13 upon an adjacent plate 11 are inclined in the opposite direction, so that the vanes 12 and 13 upon adjacent plates meet in V-shaped formation. The plane of these vanes, as shown in Fig. 2, is substantially perpendicular to the general plane of the distributor.

At the center of the distributor or grill, I employ a substantially square pyramidal member, each quarter of which corresponds to the pattern of the device as a whole in that it is parallel to the plates 11 of the corresponding quarter of the distributor. This pyramidal member 15 is secured to the adjacent plates 10 by means of vanes 16 of triangular shape, as shown more particularly in Fig. 2.

In Fig. 3 of the drawings I have shown in a conventional manner the position of the device

when installed in a wall or ceiling. The partition, such as a wall or ceiling, is represented at 17, and the air duct leading to the distributor is shown at 18. The air duct 18 and the distributor cooperate to form a passage for air or the like through the partition 17. The frame member 10 provides a border for the passage which engages the edges of the hole in the partition 17, which hole is of a size and shape to fit the duct 18 and the member 10. The distributor lies substantially flush with the surface of the partition and thus provides a neat appearing outlet for the air passage. The passage comprises a plurality of channels disposed within the bordering edge thereof described by the member 10. The walls of each of the channels are made up of the plates 11 and the vanes 12 or 13 to comprise directing surfaces which determine the direction of air flow out of the distributor.

Each vane 12 or 13, together with a portion of the plate 11, provides a directing surface for any given channel. The directing surface of each channel is thus made up of two parts: a baffle portion positioned in the path of travel of the air, and a deflecting portion which, in the embodiment shown, lies in a plane disposed in the direction of travel of the air. The baffle portion of the directing surface of each channel directs the flow of air laterally out of its direction of travel defined by the duct 18, and directs the flow of air through the channel toward the edge of the outlet. The disclosed arrangement of plates 11 is such that the baffle portions of directing surfaces of the several channels are disposed to direct the flow of air in the several directions away from the center of the passage. In the embodiment shown, each baffle portion of a given channel operates to direct the flow of air toward the nearest edge of the outlet.

The deflecting portion of the directing surface of each channel operates to direct the flow out of line with the shortest path to the edge of the outlet, and in a direction to describe an angle with the edge of the distributor. The arrangement of directing surfaces in the several channels is such that the air is diffused in all directions away from the passage and is turbulence as it leaves the distributor. To accomplish this, the deflection portions of the directing surfaces of the different channels are preferably disposed at different angles to the nearest edge of the distributor, the arrangement shown in the drawing presenting one practical embodiment. According to the arrangement shown, the plates 11 are disposed in tiers respectively spaced different distances from the edge member 10, each tier paralleling the edge member on the several sides of the duct. The several vanes 12 of one tier all describe a given angle with the edge, and the vanes 13 of the next adjacent tier describe an angle disposed in the opposite direction. Thus the channels in each tier cooperate to swirl the air in one direction as it leaves the distributor, and the channels in different tiers operate to swirl the air in opposite directions to produce a diversified directioning of air flow out of the distributor.

It will be seen that the device herein described is substantially flush with the wall or ceiling upon which it is installed, and that it occupies a space of very limited depth. Moreover, it will effect discharge of the air in a plane substantially at right angles to the direction of the flow of the entering air, and will, of course, function

equally well, regardless of its shape, whether round, elliptical, square, oblong or provided in a continuous strip of any width or length, that is, having the plates all extended in the same direction and parallel to each other.

As illustrated, the plates 11 constitute louver elements presenting louver openings therebetween, and the front and rear edges of the plates lie respectively in spaced substantially parallel planes, the plates themselves being inclined relatively to such planes. It may also be noted that the vanes 12 and 13, due to their triangular shape, lie wholly between these planes, thus providing a distributor of limited depth which may be installed in a small space to lie flush with the wall upon which it is secured.

It will readily be seen that the device can be so made as to discharge the air in all directions, or in any desired direction, depending upon the arrangement of the plates 11, and can be conveniently made by casting or other economical methods. Moreover, the distributor is equally suitable for side wall or baseboard mounting, for vertical delivery downwardly or upwardly, or both, or for ceiling mounting, for horizontal delivery, and may, of course, also be employed with cabinet heaters, cabinet air conditioners, or similar devices. In all of such cases it is desirable that the air be diffused in a plane substantially parallel to the wall or surface upon which the distributor is mounted, and it is also highly desirable to provide a distributor which will achieve this result, and which will be substantially flush with the surface upon which it is disposed.

While I have shown and described a preferred embodiment of my invention, it will be understood that it is not to be limited to all of the details shown, but is capable of modification and variation within the spirit of the invention and the scope of the appended claims.

What I claim is:

1. An air-distributing device comprising a plurality of plates disposed in spaced substantially parallel relation, the front edges of said plates lying in substantially a single plane, and said plates being inclined relatively to said plane, and vanes provided on one surface of each of said plates, said vanes extending in an oblique direction relatively to the longitudinal dimensions of the plates.

2. An air-distributing device comprising a plurality of plates disposed in spaced substantially parallel relation, the front edges of said plates lying in substantially a single plane, and said plates being inclined relatively to said plane, and vanes provided on one surface of each of said plates, said vanes extending in an oblique direction relatively to the longitudinal dimensions of the plates, and said vanes extending into the spaces between the plates.

3. An air-distributing device comprising a plurality of plates disposed in spaced substantially parallel relation, the front edges of said plates lying in substantially a single plane, and said plates being inclined relatively to said plane, and vanes provided on one surface of each of said plates, said vanes extending in an oblique direction relatively to the longitudinal dimensions of the plates, and said vanes having one side thereof extending between the front edge of one plate and the rear edge of an adjacent plate.

4. An air-distributing device comprising a plurality of plates disposed in spaced substan-

tially parallel relation, the front edges of said plates lying in substantially a single plane, and said plates being inclined relatively to said plane, and vanes provided on one surface of each of said plates, said vanes extending in an oblique direction relatively to the longitudinal dimensions of the plates, and said vanes having one side thereof extending between the front edge of one plate and the rear edge of an adjacent plate and being secured to both said plates to connect the latter together.

5. An air-distributing device comprising a plurality of plates disposed in spaced substantially parallel relation, the front edges of said plates lying in substantially a single plane, and said plates being inclined relatively to said plane, and vanes provided on one surface of each of said plates, said vanes extending in an oblique direction relatively to the longitudinal dimensions of the plates, and the vanes on one plate extending at an angle to those on an adjacent plate.

6. An air distributor comprising a plurality of flat elongated elements rigidly secured together in spaced parallel relation, the surfaces of said elements being inclined to the general plane of the distributor to present louver openings, a plurality of vanes provided on the rear face of each of said elements to project rearwardly therefrom, and said vanes extending at an oblique angle to the longitudinal dimensions of said elements and spanning the spaces between adjacent elements.

7. An air distributor comprising a plurality of louver elements secured together in parallel spaced relation to present openings therebetween, each of said elements consisting of a flat plate having spaced parallel vanes upon one surface thereof, said vanes lying in a plane substantially perpendicular to the plane of the plate and inclined to the longitudinal dimension thereof.

8. An air distributor comprising a plurality of louver elements secured together in parallel spaced relation to present openings therebetween, each of said elements consisting of a flat plate having spaced parallel vanes upon one surface thereof, said vanes lying in a plane substantially perpendicular to the plane of the plate and inclined to the longitudinal dimension thereof, and said vanes being of triangular form and tapering to an apex adjacent one edge of the plate.

9. An outlet device for an air passage comprising, an edge member defining the periphery of the passage, and a plurality of channels within the border of the edge member and arranged in a tier juxtaposed on several sides of the passage, each channel including a baffle surface disposed in the path of the air flow and describing an acute angle with a plane normal to the direction of travel of air through the passage, deflecting surfaces engaging the baffle surface and extending away therefrom toward the air approach, each deflecting surface describing an acute angle with the edge member, the baffle surfaces of the several channels being positioned to direct air flow away from the center of the passage and toward the edge thereof at several sides, the angles of the several deflecting surfaces of channels along several sides of the passage being disposed in the same direction with respect to the adjacent portion of the edge member.

10. An outlet device for an air passage com-

prising, an edge member defining the periphery of the passage, and a plurality of channels within the border of the edge member and arranged in parallel tiers juxtaposed on several sides of the passage, each channel including a baffle surface disposed in the path of the air flow and describing an acute angle with a plane normal to the direction of travel of air through the passage, deflecting surfaces engaging the baffle surface and extending away therefrom toward the air approach, each deflecting surface describing an acute angle with the edge member, the baffle

surfaces of the several channels being positioned to direct air flow away from the center of the passage and toward the edge thereof at several sides, the angles of the several deflecting surfaces of channels in a given tier along several sides of the passage being disposed in the same direction with respect to the adjacent portion of the edge member, the angles of deflecting surfaces of channels in adjacent tiers being disposed in opposite directions.

PAUL D. HARRIGAN.
